UNITED STATES PATENT OFFICE.

ROBERT L. BAILEY, OF PORTLAND, OREGON, ASSIGNOR TO A. L. MACLEOD, OF PORTLAND, OREGON.

MOTOR-CYCLE.

1,179,065.

Specification of Letters Patent.

Patented Apr. 11, 1916.

Application filed February 19, 1912. Serial No. 678,472.

To all whom it may concern:

Be it known that I, ROBERT L. BAILEY, a citizen of the United States, residing at Portland, in the county of Multnomah and State of Oregon, have invented a new and useful Improvement in Motor-Cycles, of which the following is a specification.

This invention relates to motor cycles, and has for its primary object to provide 10 a construction of the same whereby shock and vibration during riding will be greatly reduced in such a manner as to render riding as easy as possible.

A particular object of the invention is to 15 provide a construction of the front part of the machine whereby the front wheel is so mounted with respect to the front fork and front portion of the main frame, that all shock and vibration will be absorbed.

20 A further and important object of the invention is to so mount the engines that the vibration due to the propulsion of the same will be equalized and to this end the invention consists in providing horizontally opposed engines disposed symmetrically to the angle of the main frame, at which point the crank casing of the engines is mounted.

For a full understanding of the present invention, reference is to be had to the following description and to the accompanying drawings, in which—

Figure 1 is a side elevation of a motor cycle showing the features of the present invention in their proper relation. Fig. 2 35 is a side elevation of a motor cycle looking from the side opposite that shown in Fig. 1.

Throughout the following detail description and on the several figures of the drawings, similar parts are referred to by like 40 reference characters.

Referring to the drawings, 1 represents the main frame of the machine, the same being of ordinary construction and its particular structure forming no part of the 45 present invention.

2 represents the handle bars and 3 are the handles, both of ordinary construction. A flat leaf spring 4, of the structure particularly shown in the drawings, having a front 50 portion which turns under the main portion of the spring, is connected to a plate, which latter is attached to the main frame of the machine, and fastened thereto by any suitable means. A pair of false forks 5 are connected to the inner end of the inturned por-

tion of the flat leaf spring 4 and extend substantially vertically downwardly therefrom, one false fork being disposed on each side of the front wheel of the machine. The axle of the front wheel is denoted by 7, and to said axle a pair of rocker arms 6 are pivotally connected, one on each side of the wheel. The lower ends of the false forks 5 are connected to the rocker arms at points intermediate the connection of the rocker arms 6 with the axle and the upper ends of the same. A connection is thus established between the flat leaf spring 4 and the axle of the front wheel, through the rocker arms 6 as intermediate members. The upper ends 70 of the rocker arms 6 are connected to the flat leaf spring 4 by means of the rods 6^a, the latter being connected to the spring near the rear portion of the latter, at points where the spring is connected to the main 75 frame. The front forks of the machine are denoted by 8, these being constructed of bifurcated form, as in the ordinary manner, one branch passing to each side of the front wheel and being connected at their lower 80 ends with the respective upper ends of the rocker arms 6. By virtue of the construction described, consisting of the connections of the axle, rocker arms, false forks, the front fork and the flat leaf spring, all shock 85 and vibration due to rough riding will be absorbed, thus rendering the riding easy and pleasant. The front wheel is denoted by 9; 10 is the tire of the front wheel and 11 is the mud guard therefor, the latter being of 90 ordinary construction but is connected to the rocker arms by means of the rods 11^a, one of which is arranged on each side of the front wheel and which serve as braces for the mud guard and tend to reduce and 95 equalize vibration.

A rod 1^a connects the two downwardly extending portions 1^b and 1^c of the main frame 1, the rod 1^a being disposed in a substantially horizontal direction, as is clearly 100 shown. Resting on the rod 1^a and between the latter and the outer portion of the main frame, the gasoline tank 18 is disposed, the same being provided with a filling cap 12 which is also provided with a stop or shut-off valve 13 but which forms no part of the present invention. Disposed adjacent to the gasoline tank 18 and between the rod 1^a and the upper part of the frame 1 is a lubricating oil tank 17 having a filler cap 15 110

analogous to that formed on the gasoline tank and a small pump 14 is provided for the purpose of forcing the lubricating oil down to the crank casing.

19 represents a small pipe substantially vertically disposed which leads the gasoline from the tank to the carburetor, and the downwardly extending tube 20 conducts the lubricating oil from the oil tank to the crank casing, which latter is denoted at 27.

The saddle of the machine is shown at 16, the same having the front spring 16^a and the rear springs 16^b.

The carburetor of the machine is represented at 21, the same being of ordinary construction, and is disposed between the downwardly extending portions 1^b and 1^c of the main frame, it being mounted adjacent to the crank casing 27, as shown. A control wire 22 connects the carburetor 21 with the handle bars and is provided for the purpose of regulating the feed of the gasoline to the carburetor, and to also control the mixture of the product which passes through the carburetor.

23 represents the manifold and after the proper mixture is produced in the carburetor, the same is discharged into the manifold, by means of which it is conveyed directly to the engine cylinders.

It is to be noted that the arms of manifold 23 are laced through the frame, one arm extending at one side of portion 1^c and the other arm at the other side of portion 1^b of the frame, so that the carburetor is sustained in the most accessible position possible while, by being in the line of the frame, it is free from danger of injury from contact of the legs or feet of the operator. This arrangement of the manifold also provides a simple and efficient means of accommodating the disposition of one cylinder at one side or the other while horizontally alined.

24 is a magneto of ordinary construction and 25 is a control wire leading from the magneto through the frame of the machine to the handle bars, by which the magneto may be controlled in the ordinary manner. The construction and connections of the wires 22 and 25 form, however, no part of the present invention and need not be further described.

26 represents the magneto gear casing in which a chain of gears is housed, this being for the purpose of properly timing the explosions which take place in the engine cylinders.

The crank casing 27 hereinbefore referred to is disposed at the angle produced by the connection of the downwardly extending portions 1^b and 1^c of the main frame in such a manner that the crank axle therein will be disposed exactly at the connection of said members.

25 The manifolds 23 are provided with the

intake portions 28 where they connect with the valve chambers 29, two of the latter being provided, one on each side of the crank casing, and lying in a substantially horizontal plane with respect thereto.

The engine cylinders are denoted by 30 and according to the present invention, two horizontally opposed cylinders are provided, one to each side of the crank casing, and symmetrically disposed with relation thereto so that the common middle plane of the cylinders coincides with the plane in which the crank axle lies, the latter not being shown.

By the arrangement just described of the two opposed engine cylinders lying in a substantially horizontal plane which includes the crank axle, and by the provision of arranging the crank casing and crank axle at the angle produced by the two downwardly extending portions 1^b and 1^c of the main frame, the vibration due to the propulsion of the engines is equalized. Thus no shocks or vibration can be transmitted to either the front portion or the rear portion of the machine, as the same is taken up and equalized at the angular connection of the downwardly extending portions of the main frame. This feature constitutes a great advantage toward making the riding of the machine easy, the vibration transmitted from the engines to the front and rear wheels having been heretofore a decided disadvantage.

The engines are provided with exhaust valve stems 31; 32 is the casing for the cam gearing for the valve stems; and 33 is the exhaust manifold which leads directly to the muffler 34, the latter being disposed below the rear cylinder 30.

The pedals of the machine are denoted by 35.

36 is a pedal control rod for operating the brake band, the particular structure and connections thereof not being fully illustrated herein, while 37 is a rod or bar leading from the pedals to the clutch of the rear wheel.

38 is the axle of the rear wheel; 39 is the brake drum therefor and 40 is housing for the gears by which the rear wheel is propelled. The housing 40 also contains the clutch members of the rear wheel, but the same are not shown in the present case.

41 represents the rear fork terminal, the object of which is to connect the frame members which terminate near the rear axle with the centrally disposed mechanism of the machine.

The driving shaft for the rear wheel is not shown but the casing in which the same is housed is denoted by 42, this casing connecting with the transmission casing 44, which latter is in turn connected with the crank casing 27.

The means for automatically shifting the gears so as to obtain a change of transmission to and from high and low speeds and neutral, is particularly described in a co-pending application and may here be briefly referred to and consists of the lever 47 pivoted to the main frame 1, the lever being movable over a sector plate 47^a which is provided with a plurality of openings in which 10 a pin 47^b on the lever may engage. The lever is connected with a rod 46^a which latter is connected with the energy storing device 46 consisting of a barrel in which springs are disposed in such a manner that when 15 the rod 46^c connected to the lower portion of the energy storing device 46 and working therein, is held in a fixed position, the springs within the casing 46 will be compressed and the energy stored up by such 20 compression may be used when the rod 46^c is released. The latter is connected with the bell crank lever 45 pivoted to the transmission casing and connected at one end to a rod 45^a which enters the transmission casing 25 and effects the shifting of the gears so as to produce the change of transmission. Movement of the rod 45^a is controlled from the

pedals through the instrumentality of the lever device 43 which, however, need not be described herein.

30

Having thus described the invention, what is claimed as new is:

In a motor cycle, the combination, with a frame, of an internal combustion engine sustained at the lower portion of the frame 35 and comprising a plurality of cylinders, a carbureter disposed in the line of members of the frame, and a manifold for delivering gas to the cylinders interlaced through the members of the frame with one arm of the 40 manifold extending from the carbureter at one side of one of the frame members to one of the cylinders and the other arm of the manifold extending past another frame member at the opposite side thereof to the 45 other cylinder.

In testimony that I claim the foregoing as my own I hereunto attach my signature in the presence of two witnesses.

ROBERT L. BAILEY.

In the presence of—

THOMAS BILYEW,
E. O'GARA.
